MAGNETIC SEPARATOR FOR SHEET FEEDING APPARATUS

Lloyd W. Wall, Oaklawn, Ill., assignor to Caspers Tin Plate Company, Chicago, Ill., a corporation of Illinois

Application November 23, 1948, Serial No. 61,643

8 Claims. (Cl. 271—18)

1

This invention relates to apparatus for successively feeding metal sheets from a stack and includes an arrangement of permanent magnets to insure feeding of a single sheet at a time.

Specifically, the invention deals with a permanent magnet separator for stacked metal sheets and an automatic stack lifting device coacting with the separator to maintain the top sheet of the stack at a desired level irrespective of the degree of deflection of the top sheets in the stack under the influence of the magnetic field induced by the magnets.

In accordance with this invention, a sheet metal feeding machine with an elevator for a stack of metal sheets is equipped with permanent magnets to act on the rear end and sides of the top metal sheets in a stack of sheets being acted upon by the machine. These permanent magnets are so mounted that they will be deflected by the stack of sheets in the event of misalignment, thereby insuring against damage of the sheets. The magnets induce magnetic fields in the upper sheets of the stack and are arranged so that the induced fields will have the same polarity in the corresponding areas of adjacent sheets, thereby causing these sheets to separate from each other. This separation is most pronounced at the sides of the sheets and at the outer ends of the rear ends of the sheets so that the central portions of the rear ends of the sheets will be in substantial contact. An elevator control unit is mounted to act on the substantially non-deflected portion of the top sheet in the stack so that the stacks will not be raised under the influence of the separated portions of the sheets. Vacuum operated suction cups deliver the successive top sheets of the stack to mechanism which forwards the sheets out of the front end of the machine. As the sheets are removed from the stack, the elevator actuator descends to control a lifting mechanism which will raise the elevator for maintaining the upper sheets of the stack within the magnetic fields induced by the permanent magnets and in a position so that the top sheet of the stack will be properly gripped by the suction cups.

It is, then, an object of this invention to provide a sheet metal feeder for successively delivering metal sheets from a stack while maintaining the top sheets of the stack in a separated condition to insure against a multiple sheet feed.

A further object of this invention is to provide an arrangement of permanent magnets on

2

a sheet metal feeder which will separate the top sheets of a stack in the feeder and will cooperate with an elevator mechanism to maintain a desired level for the top sheets of the stack irrespective of variations in deflection of the sheets by the magnetic fields induced therein.

Another object of the invention is to provide an arrangement of permanent magnets around the rear end and sides of a stack of sheets in a sheet delivery machine for deflecting the sides and rear ends of the top sheets in the stack while maintaining the central portions of these top sheets in contact to retain the true top level of the stack.

15 A further object of the invention is to provide a magnet assembly for a sheet metal feeder wherein the magnets are deflected to accommodate misalignments in successive stacks of sheet material supplied to the feeder.

20 A still further object of the invention is to provide a magnetic separator for a sheet metal feeder which coacts with a vacuum lifting device and a stack-elevating mechanism without interfering with the efficient operation of these parts of the machine.

25 A specific object of the invention is to provide an electrically actuated elevator mechanism for a sheet feeder machine which is not influenced by magnetic separation of the sheets.

30 A still further specific object of the invention is to provide a magnetic separator for a sheet metal feeder which does not require a source of power and which is sufficiently compact to be readily installed without rearrangement of parts of the feeder machine.

35 Other and further objects of the invention will be apparent to those skilled in the art from the following detailed description of the annexed sheets of drawings which, by way of a preferred example only, illustrate one embodiment of the invention.

40 On the drawings:

Figure 1 is a rear end elevational view of the metal sheet feeder machine of this invention equipped with the permanent magnet separators of this invention.

45 Figure 2 is a fragmentary view of a portion of the rear end of the machine of Figure 1 illustrating the manner in which the permanent magnet mountings permit deflection of the magnet in the event of misalignment between the stack of metal sheets and the magnet.

50 Figure 3 is a top plan view of the machine of Figure 1. Figure 4 is a side elevational view of the ma-

55 Figure 4 is a side elevational view of the ma-

chine of Figure 1, illustrating the right side of the machine as viewed from Figures 1 and 3.

Figure 5 is a fragmentary cross-sectional view, with parts in side elevation, and with the stack of metal sheets omitted, taken along the line V—V of Figure 1.

Figure 6 is an enlarged fragmentary view of a part of the machine viewed along the line VI—VI of Figure 3.

Figure 7 is a detail view, with parts broken away, of a portion of the machine viewed along the line VII—VII of Figure 3.

Figure 8 is a top plan view of one of the side magnet mountings of the machine.

Figure 9 is a transverse cross-sectional view taken along the line IX—IX of Figure 8.

Figure 10 is an isometric view of one of the magnet mountings for the rear end of the machine.

Figure 11 is a diagrammatic perspective view illustrating the manner in which the permanent magnets induce magnetic fields in the top sheets of the stack to effect separation of the sheets.

As shown on the drawings:

The machine 10 of Figures 1 to 5 includes framework 11 straddling a space 12 adapted to receive a stack of metal sheets as will be more fully hereinafter described. The frame 11 has bearings on the upper end thereof of rotatably carrying shafts 13, 13 on both sides of the machine. Each shaft 13 has a pair of chain sprockets 14, 14 fixed thereto and receiving chains 15 in link-engaging relation around the upper halves thereof. Four chains 15 are thus provided and these chains support an elevator platform composed of slings 16 disposed in the space 12. A transverse shaft 17 has worms 18 on the ends thereof meshing with worm gears 19 on the shafts 13, 13 to drive these shafts. A main drive shaft 20 (Figure 4) is connected through bevel gears 21 with a power input shaft 22 carrying a gear 23 that meshes with a gear 24 on a transverse drive shaft 25 (Figure 1). A second gear 26 on the shaft 22 meshes with a gear 27 on a stub shaft 28 at the right hand end of the machine as viewed in Figure 1, and this shaft 28 drives a pulley 29 which actuates a belt 30 (Figure 4) for driving a roller shaft 31 which actuates belts 32 to advance sheets out of the machine. A link 33, best shown in Figures 1 and 6, is pivotally connected to the gear 26 to be reciprocated thereby for rocking a pawl carriage 34 on the worm shaft 17. The carriage 34 has a pawl 35 thereon adapted to engage a ratchet 36 secured to the shaft 17 for rotating the shaft whenever a solenoid 37 on the carriage 34 is energized to depress its plunger 38 against pressure of the spring 39 for rotating a pawl support 40 relative to the carriage 34 so that the pawl will engage the ratchet teeth. When the worm shaft 17 is driven, the elevator shafts 13 are rotated for raising the elevator platform 16.

The drive shaft 25, as shown in Figure 1, has an eccentric 41 thereon which swings an arm 42 on a forwarder shaft 43. This forwarder shaft 43, as shown in Figure 1, has brackets 44 mounted thereon and carrying suction cup housings 45. These housings are swung through an arc when the shaft 43 is oscillated. As shown in Figure 5, a suction tube 46 projects from the lower end of the housing 45 and a rubber suction cup 47 is mounted on the bottom of the tube. A spring loaded piston (not shown) in the housing 45 raises and lowers the tube 46 and is actuated by vacuum. A vacuum hose 48 evacuates the tube and suction cup and controls the piston in the

housing 45. A shaft 49, driven from the drive shaft 25, drives a sprocket chain 50 to actuate a vacuum pump (not shown) for the vacuum hoses 48.

As best shown in Figure 3, the frame 11 has horizontal pins 51 at the rear end thereof projecting into the space 12 straddled by the frame and supporting the front ends of rods 52 paralleling the sides of the frame and secured at their rear ends to brackets 53 which also carry the forwarder shaft 43. A bar 54 transversely spans the rear end of the space 12 and has adjustable clamps 55 on the ends thereof supported on the rods 52. This bar 54 is thus adjustable forwardly and rearwardly on the rods 52.

Clamping brackets 56 on the bar 54 carry bars 57 which extend forwardly in the space 12 to straddle the sides of a stack of sheets on the elevator platform or slings 16. The bars 57 have clamping brackets 58 adjustably mounted thereon and these brackets have depending lugs 58a straddled by ears 59a of a magnet carrier 59. Pivot pin 58b extends through the lug and ears to pivotally suspend the carrier 59 on the brackets 58. The carrier 59, as best shown in Figures 8 and 9, has an elongated angle bar member 59b on which three semi-cylindrical or U-shaped permanent magnets 60 are mounted. These magnets 60 each have boss portions 60a at their sides receiving mounting bolts 61 therethrough. These mounting bolts 61 are threaded into the angle bar 59b to support the magnets in spaced side by side relation along the length of the bar. A non-magnetic shield 62 composed of sheet metal, such as brass or the like, is interposed between the magnets and the bar 59b and is held on the bar by the magnet mounting bolts 61. This shield has a front wall 62a, best shown in Figure 9, overlying the open front faces of the magnets 60 and converging toward the rear wall 62b thereof along a smoothly curved or rounded lower end portion. The shape of the shield is such that when a stack of metal sheets 63 on a skid 64 is deposited on the slings 16 of the elevator in misaligned position, and the elevator is then raised to move the stack to its operating level, the rounded end of the shield will ride over the side edges of the sheets to tilt the magnet assembly about the pivot pin 58b to an out of the way position, thereby preventing damage of the assembly and the edges of the sheets. The stack can then either be quickly aligned on the elevator, or the magnet units can be shifted by sliding the clamps 56 on their support bar 54. Likewise, the clamps 58 can be adjusted on their support bars 57. The tilted position assumed by a side magnet assembly when the stacks are misaligned is illustrated in Figure 2.

Adjustable clamps 65 are mounted on the bar 54 between the brackets 56. These clamps 65 have brackets 66 thereon carrying cylinders 67 for a rear end set of suction cups 68 to pick up the outer sides of the rear end of the top sheet on the stack 63. Each suction cup 68 is evacuated through a tube 69 slidable in the cylinder 67 and actuated by a vacuum and spring-controlled piston (not shown) to be raised and lowered for engaging the top sheet of the stack 63 and for raising the sheet. The cylinders 67, unlike the front cylinders 44, are not shifted during their sheet-lifting operation. The arrangement of the suction cups and cylinders is such that the suction cups will be pressed against the top sheet to firmly grip four spaced portions 70 of the sheet, and the cups will then be raised

to lift the top sheet, and the front cylinders 45 will then be tilted to throw the raised sheet forwardly as the vacuum is released, whereupon the forward edge of the sheet will be fed to the feed rollers 70 shown in Figure 4, while the belt 32 will advance the sheet away from the space 12. The rear vacuum cups 68 are evacuated from the same vacuum pump described above for the front vacuum cups 47 through a set of flexible hoses 72.

The clamps 65 also have a pair of lugs 65a projecting rearwardly from their rear faces and slidably receiving rods 73 therethrough as best shown in Figure 10. These rods have collars 74 thereon for resting on the lugs 65a to retain the rods in mounted relation on the clamp. Blocks 75 are secured to the lower ends of the rods 73 and receive a shield 76 of non-magnetic material thereagainst. Cooperating blocks 77 overlie the bars 75 with the rear wall 76a of the shield therebetween. A single semi-cylindrical or U-shaped permanent magnet 78 with bosses 78a at the sides thereof receives studs through the bosses thereof. These studs extend through the blocks 77 and are threaded into the blocks 75 to anchor the shield and the magnet to the rods. The front wall 76b of the shield has a curved lower end similar to the front wall 62a of the shield 62.

As shown in Figure 2, when the rear end of the stack of sheets 63 is misaligned in the space 12, as the elevator 16 raises the stack, the curved wall 76b of the shield 76 will ride on the sheets to raise the rear magnet assembly, since the rods 73 are slidably in the lugs 65a thereby preventing damage to the magnet assemblies and to the sheets.

The bar 54 has another adjustable clamp 80 thereon between the clamps 65. This clamp 80 has a tubular housing 81 best shown in Figure 7 slidably carrying a vertical rod 82, the lower end of which has a rounded head 83. A channel-shaped strap 84 has top and bottom flanges secured to the rod 82 above and below the housing 81 and a vertical side wall equipped with a cam 85 for actuating the plunger 86 of an adjacent electric switch 87. As the rod 82 is raised in the housing 81, the cam 85 permits the plunger 86 to move outwardly, thereby opening the switch 87. However, as the rod 82 descends, the cam 85 forces the plunger 86 inwardly to close the switch. The switch 87 controls an electric circuit including the solenoid 31 for actuating the panel support 40. When this circuit is closed, the solenoid 31 depresses the spring 39 to the position shown in Figure 6, thereby rocking the pawl carrier 40 and causing the pawl 35 to engage the ratchet 36 whereupon the shaft 17 will be driven as the gear 26 oscillates the carriage 34. When the shaft 17 is driven, the worms on the ends thereof drive the elevator shafts 13 to raise the elevator.

The clamp 80 is positioned, as shown in Figure 1, so that the rounded end 83 of the rod 82 will rest on the top sheet of the stack of sheets 63 at the longitudinal center of the stack adjacent the rear edge thereof as indicated in Figure 3. The clamp 80 is adjusted relative to the clamps 65, 56, and 58, so that the portion of the stack acted on by the end 83 will represent the true solid height of the stack. Thus, while the magnet 60 and 78 cause the sides and outer ends of the rear edges of the sheets in the stack 63 to spring apart, the arrangement is such that the head 83 acts on a solid portion of the stack where the sheets have not been deflected or sprung

apart. In this manner, the switch is actuated by the true level of the solid stack and is only closed when this true level drops below a predetermined height, whereupon the circuit will be closed to energize the solenoid, and the elevator will be raised to reclaim the original level for the top sheet of the stack. It should be noted that upward movement of the top sheet as it is removed from the stack by the suction cups will not be impeded by the head 83 and this upward movement will have no effect in closing the switch 87, even though the head is raised. The switch is set to close only when the head drops below a predetermined level.

The magnets 60 along the sides of the sheets are arranged so that the adjacent portions thereof are of the same polarity. As illustrated in Figure 3, the center magnet 60 of each assembly has its south pole adjacent the south pole of one end magnet and its north pole adjacent the north pole of the other end magnet. The magnet fluxes induced in the edges of the sheet 63 thus extend from the north to the south pole of each magnet as indicated by the dotted lines 88. The magnets 78 are spaced quite far apart but nevertheless have the same poles thereof adjoining each other so that the magnetic flux 89 induced in the rear edges of the sheets 63 will extend across the poles of each magnet and not from one magnet to another. This arrangement causes the sheets to spring apart as best shown in the diagrammatic view of Figure 11 wherein the magnetic fluxes 88 at the sides of the sheets will create superimposed charges of the same polarity, causing the sheets to spring apart along their sides forwardly from the rear end edges thereof. Likewise, the fluxes 89 induced in the rear edges of the sheets adjacent the outer ends thereof will cause the plates to spring apart at the outer ends of the rear edges. Because the sheets are quite thin and flexible, they will assume deformed or bowed positions with their longitudinal central portions at the rear end thereof being in firm solid contact with the next succeeding sheet so that, as explained above, the head 83 of the switch actuator acts on the top sheet of a solid stack of sheets representing the true height of the stack. As explained above, the magnets 60 and 78 are of the permanent type. They are preferably composed of Alnico alloy and have a very high magnetic strength for their size and weight. Therefore, very small magnets can be used and the adjustable suspension arrangement in the space 12 of the machine 10 is made feasible.

From the above descriptions, it should therefore be understood that this invention provides a feeding machine which will successively feed metal sheets off of the top of a stack of sheets by means of suction cups and in which delivery of more than one sheet at a time is prevented by an arrangement of permanent magnets mounted adjacent the stack of sheets to cause the top sheets in the stack to spring apart due to induced magnetic fluxes. The machine of this invention includes an automagnetic stack elevator controlled by a gravity button which is so positioned relative to the magnets that it will always act on the top sheet of a solid portion of the stack even though the outer edges of this sheet are raised from the stack.

It will, of course, be understood that various details of construction may be varied through a wide range without departing from the principles of this invention and it is, therefore, not the purpose to limit the patent granted hereon other-

wise than necessitated by the scope of the appended claims.

I claim as my invention:

1. A magnetic separator for metal sheet feeders which comprises an assembly of permanent magnets extending along and arranged to act on the edges of a stack of sheets in the feeder, each of said magnets having a non-magnetic deflecting shield extending thereover and beneath the lower margins thereof, supports for said magnets including support bars spaced above and extending generally along the edges of the sheets of a stack of sheets and mounted for adjustable movement with respect to each other in accordance with the perimeter of the sheets of the stack of sheets, and vertically movable supports carrying said magnets and mounted on said support bars for adjustment therealong, said vertically movable supports mounting said magnets on said support bars to accommodate said magnets to freely move vertically upon engagement of the top surface of a misaligned sheet with said deflecting shields.

2. A magnetic separator for a metal sheet feeder machine having a support for a stack of metal sheets which comprises a magnetic carrier on said feeder machine, a plurality of magnet assemblies adjustably suspended from said carrier to lie adjacent the edges of the upper sheets of a stack of metal sheets on the support of the feeder machine, supports for the assemblies on the carrier accommodating free upward movement of the assemblies and a non-magnetic shield extending over the magnet of each assembly and adapted to be engaged by a misaligned sheet of a stack of sheets to move the associated magnet assembly with the engaged sheet on the sheet support of the feeder machine relative to the carrier without damaging the machine.

3. A magnetic separator for a metal sheet feeder machine having a support for a stack of metal sheets which comprises a magnet carrier on said feeder machine, a plurality of permanent magnet assemblies adjustably suspended from said carrier to lie adjacent the edges of the upper sheets of a stack of metal sheets on the support of the feeder machine, pivot supports for the assemblies accommodating tilting of the assemblies to raised positions, and a non-magnetic shield over the magnet of each assembly having a rounded rocking bottom to tilt the assembly about its pivot when a misaligned sheet in the stack of sheets is raised into engagement with said rocking bottom.

4. A magnetic sheet separator for a metal sheet feeder comprising an open frame, a carrier mounted to extend across the open portion of said frame, a plurality of brackets mounted on said frame and depending therefrom, a magnet carrier pivotally mounted on each of said brackets for pivotal movement about axes extending parallel to the edges of the sheets of the stack of sheets, permanent magnets carried by said magnet carrier in side by side relation with like poles lying adjacent each other, each of said permanent magnets having a non-magnetic shield extending along the poles thereof and depending therefrom and converging in a direction away from its poles to deflect said magnet about the pivot of said carrier when a misaligned sheet of a stack of sheets is raised thereagainst.

5. A magnetic sheet separator for a metal sheet feeder comprising an open frame, a bar mounted to extend along the open portion of said frame and for adjustable movement thereacross for alignment with one edge of the sheets, a pair of

support bars extending perpendicularly to said bar and mounted thereon for adjustable movement with respect thereto for alignment with the side edges of the sheets, brackets adjustably mounted on said bars, means for holding said brackets in position on said bars, a permanent magnet pivotally connected to each of said brackets beneath said bars and depending therefrom, and magnetic shields extending along the forward and rear faces of said magnets to extend along the edges of the sheets, said shields converging in directions away from the side edges of the sheets toward their lower ends and forming deflecting shoes pivotally moving said magnets in an upward direction upon engagement with a misaligned sheet.

6. A magnetic separator for a metal sheet feeder comprising an open frame, a support bar mounted on said frame at its ends and extending along the open portion thereof, a pair of transverse support bars adjustably mounted on said support bar for movement therealong and extending generally perpendicularly thereto, brackets adjustably mounted on said bars, means for holding said brackets in position on said bars, a permanent magnet pivotally connected to each of said brackets and depending therefrom and being free for pivotal movement about an axis parallel to the longitudinal axes of the respective bar, said bars being adjustable to position said magnets to extend along the edges of the sheet and said magnets being arranged with the like poles adjacent each other, to induce like magnetic fluxes in the edges of the sheets and separate the sheets by repulsion, non-magnetic shields extending along the faces of said magnets adjacent the sheets and depending therefrom and diverging from the sheets to form deflecting shoes pivotally moving the magnets in an upward direction upon engagement with an upwardly moving misaligned sheet.

7. In a sheet feeder for a stack of metal sheets, an open frame, an elevator carried by said frame for raising a stack of metal sheets along said frame, a support bar extending along the open portion of said frame and mounted thereon for adjustable movement with respect thereto, spaced support bars extending perpendicularly of said bar and mounted thereon for adjustable movement therealong, said bars being spaced above the sheets on said elevator and being adjustable to extend along the sides and edges thereof, a plurality of permanent magnets suspended from said bars and mounted thereon for pivotal movement with respect thereto about axes extending longitudinally thereof and having similar magnetic poles adjacent each other to separate adjacent sheets by repulsion, and being freely movable to pivot in an upward direction upon engagement by a misaligned sheet.

8. In a sheet feeder for a stack of metal sheets, an open frame, an elevator carried by said frame for raising a stack of metal sheets along said frame, a support structure adjustably mounted on said frame to extend within the open portion thereof and including a support bar extending along the open portion of said frame, and spaced support bars extending perpendicularly from said bar, said support structure being spaced above the sheets on said elevator at all times and being adjustable into alignment with the side and edges thereof, and a plurality of sheet separating magnets suspended from said bars and mounted for pivotal movement with respect thereto about axes extending longitudinally of

said bars with similar magnetic poles adjacent each other, to set up repulsion magnetic fields in the adjacent sheets, said magnets having non-magnetic shields extending along opposite sides thereof and depending therefrom to extend along the edges of the sheet, with the bottom edges thereof diverging from the sides thereof, adjacent the edges of said sheets, and forming engaging shoes pivoting said magnets in an upward direction upon engagement by a misaligned sheet on 10 said elevator.
